(57) **CLAIM**

The ornamental design for a credit card, as shown and described.

DESCRIPTION

The patent file contains one drawing executed in color. Copies of this patent with color drawing will be provided by the Office upon request and payment of the necessary fee. FIG. 1 is a color photograph of the top plan view of a credit card showing my new design wherein the top surface is divided into five colored regions in which adjacent regions are differently colored as shown, and includes an eagle design, words, numerals, and letters.

FIG. 2 is a front elevational view thereof, with the rear elevational view being identical to FIG. 2.

FIG. 3 is a left-side elevational view thereof, with the right-side elevational view being identical to FIG. 3.

FIG. 4 is a bottom plan view of the back thereof; and, FIG. 5 is a cross-sectional view along line 5—5 of FIG. 1, and shows the three rectangular holes passing through the entire thickness of the card from the face of the credit card to back thereof.
